UNITED STATES PATENT OFFICE.

JOHN V. WHITBECK, OF CLEVELAND, OHIO.

DESIGN FOR A CAR-BODY.

45,579.

Specification for Design.

Patented Apr. 7, 1914.

Application filed February 6, 1914. Serial No. 817,075. Term of patent 3½ years.

To all whom it may concern:

Be it known that I, JOHN V. WHITBECK, a citizen of the United States, and a resident of Cleveland, county of Cuyahoga, State of Ohio, have invented a new, original, and ornamental Design for Car-Bodies, of which the following is a specification, reference being had to the accompanying drawing, forming a part thereof.

In the drawings: Figure 1 is a side eleva-

tion of an automobile car body embodying my new design; and Fig. 2 is a front elevation of the same.

I claim:

The ornamental design for a car body, as shown.

JOHN V. WHITBECK.
